VENTILATING AND HEATING DEVICE

Louis J. Jenn, Indianapolis, Ind.

Application October 3, 1949, Serial No. 119,225

6 Claims. (Cl. 98—33)

1

This invention relates to a device comprising an integral unit which provides ventilation and a means of auxiliary heat to a room. This device is adapted to be completely recessed in a wall with only an ornamental grille visible. The device is constructed and arranged to withdraw air from a room, circulate air in a room or warm the circulating air if it is so desired. It is particularly desirable to have such a device in a bathroom to remove moisture laden air or to circulate warm air and it is also desirable to have such a device in a kitchen to withdraw air laden with cooking odors or hot air resulting from the use of a stove or oven.

It is an object of this invention to provide a single unit device which can withdraw air from a room or circulate the same and heat it if it is so desired.

It is another object of this invention to provide a ventilating device comprising a housing or casing which can be conveniently disposed in a wall between adjacent studding and communicate with a room with only a grille being visible.

It is a more specific object of this invention to provide a ventilating device comprising a casing constructed and arranged to be disposed and supported between a pair of studdings, the same having an open top and upper and lower front openings, a fan for drawing air into said lower opening, a heating means extending across said upper opening and a damper for directing said air either out of said top or through said upper opening and through said heating means.

These and other objects and advantages of the invention will be fully set forth in the following description made in connection with the accompanying drawings in which like reference characters refer to similar parts throughout the several views and in which:

Fig. 1 is a perspective view showing the device recessed in a wall between the studding;

Fig. 2 is a view in front elevation showing the grille and part of the casing in dotted line;

Fig. 3 is a view in front elevation with the grille removed showing one type of fan;

Fig. 4 is a view in vertical section taken on line 4—4 of Fig. 3 in the direction of the arrows;

Fig. 5 is a view in front elevation with the grille removed showing a propeller type fan and some parts being broken away; and

Fig. 6 is a view in vertical section taken on line 6—6 of Fig. 5 in the direction of the arrows.

Referring to the drawings, in Fig. 1 a perspective view of a part of a building structure is shown

55

comprising the studding 10, the joists 11, the rafters 12 and the roof portion 13. This is of usual construction. Mounted on a cross member 15 secured between adjacent studs 10, as by nails 16, is one embodiment of the ventilating device 20 of this invention, the same being shown in perspective. As shown, this device can be completely disposed between adjacent members of studding and of course could be of different sizes. 10 The applicant's device comprises a housing or casing 21. This housing 21 is box-like and generally rectangular in horizontal and vertical section and is made of a sheet material, such as wood or metal. The said housing has a bottom 21a secured to cross piece 15, sides 21b, a rear wall 21c and an open top 21d. The said housing has upper and lower front openings 21e and 21f respectively. The upper front portion 21g adjacent the upper edge of said housing 21 is recessed 15 slightly. A pyramidal cap 22 is provided which extends upwardly from and fits about the upper edge portion of said housing 21. The said cap has a cylindrical portion 22a. A discharge duct 23 is provided shown as of cylindrical form which extends upwardly between the studding into the attic or upwardly through the roof. If extending through the roof, as shown in Fig. 1, said discharge duct may be provided at its top with a cap 24.

Extending transversely across the front of said housing are spaced horizontal cross members or bars 25, 26 and 27 secured adjacent the top, adjacent the middle and adjacent the bottom thereof respectively. These cross members may be made of wood, are rectangular in vertical section and may be secured to the sides of said housing in any suitable manner, as by nailing. The cross members 25 and 26 serve to define the upper and lower openings 21e and 21f. Secured to and extending between members 25 and 26 in the upper opening 21e are a plurality of spaced electrical heating coils or conductors 28, forming a heating unit. Electrical current to said coils or conductors is controlled by a toggle switch 29 disposed in a chamber in member 26 and having a forwardly projection handle 29a. Electrical current is provided through a suitable conductor 30.

Secured to the inner side of cross member 25 by screws 32 is a hinge 35 to which is swingably secured a damper 36. Said damper is made of sheet material, such as metal. Said damper is moved in an arc backwardly and upwardly and said hinge is so constructed as to position said damper at either end of the arc in which it moves or at an intermediate point. For movement of

said damper, a handle 37 is pivotally secured to the same adjacent its lower end by a pivot 24. Said handle is formed of a bar or rod extending to the front of housing 21 and having an upturned end. Damper 36 is disposed in the upper front of casing 21 and at the rear of coils or conductors 28.

Referring to Figs. 3 and 4, a fan housing 42 is provided and is secured in the lower part of casing 21 and is spaced inwardly somewhat of the front and back of said housing. Said fan housing is preferably made of sheet material, such as metal, and has a generally cylindrical shape with an upper portion curved upwardly to form a duct 42c leading into the upper portion of casing 21. A plate 43 extends across casing 21 through which the duct 42c passes and by which said duct is positioned. A circular air intake opening 42d is provided in the front 42a of the said fan housing. Brackets 45 having circumferentially and equally spaced radial arms are secured exteriorly to the front and back of the said fan housing respectively by bolts 49 and are centered thereon respectively in alignment with one another. Said brackets are secured to the said fan housing by screws 46. An electrically driven motor 47 is provided and is disposed in fan housing 42 and secured to the front bracket 45 by bolts 48. Motor 47 is provided with an armature or driving shaft 49 which is journaled in said brackets 45. Positioned about said motor and secured to shaft 49 is a squirrel cage type fan 50 rotating freely about motor 47. A toggle switch 44 for controlling motor 47 is provided.

A modification of the above described construction is shown in Figs. 5 and 6. Secured to the front of the lower chamber is a face plate 51 provided with a circular opening 51a centered therethrough and forming an air intake. A motor 52 is provided having an armature or driving shaft 53 extending forwardly therefrom. Said motor is positioned centrally of opening 51a and disposed in the lower front of casing 21. Motor 52 is secured by diagonally extending and cross braces 54 having their outer ends bent at right angles and secured respectively to cross members 26 and 27 and their inner ends similarly bent and secured respectively by bolts 58 to the housing motor 52. A propeller blade fan 59 is secured to shaft 53 and is driven thereby. A toggle switch 44 for motor 52 is provided secured to member 27. A different form of handle 37a is provided for damper 36 and is of upwardly curved form and secured adjacent the upper end of said damper.

A deflecting plate 60 is provided at the rear of fan 59. Said plate extends substantially the width of said casing 21. It is secured by screws 61 at its lower edge portion to cross member 27. Said plate is inclined upwardly and rearwardly and is secured in any suitable manner, as by welding, to the rear of the casing 21 at the upper portion of its lower chamber.

Overlying the front of housing 21 is an ornamental grille 65 provided with a plurality of openings formed of spaced vertical bars 66 in its lower portion and spaced radially extending bars 67 in its upper portion to permit the free movement of air therethrough. Openings 68 and 69 are provided in the said grille to respectively accommodate toggle switches 29 and 44. Said grille is secured to said housing 20, as by screws 69a or other commonly used fastening means.

In operation, the applicant's device will be recessed in a wall, as shown in Fig. 1. Housing 21 is conveniently disposed between adjacent stud-

ding 10 and duct or conduit 23 extends upwardly between said studding. Cross piece 15 can be located at any desired height. Only the ornamental grille will be visible on the wall of the room, such as a bathroom or kitchen. The discharge duct may lead into the attic of the dwelling or building or it may extend up through the roof. This single unit ventilating device has a high degree of utility in performing three related functions. By positioning the damper into a forward or vertical position, as is shown in Fig. 6, the discharge duct will be open to its full extent. Then by turning on the blower or fan, air will be withdrawn from the room through the opening into the lower portion of the casing 21 and it will be forced upwardly and out through the exhaust duct 23.

When the damper is pushed backwardly to its full extent, as shown in Fig. 4, the discharge duct 20 will be closed off completely. When the fan or blower is turned on it circulates the air in the room by drawing it in through opening 21f into the lower portion of the casing 21 and blowing or forcing it back into the room through the upper opening 21d. If desired, the heating coils 28 25 may be turned on when the air is circulated back through the room. This air passes through the heating coils and is warmed in its passage. Thus this device may serve as an auxiliary heating unit.

By positioning the damper at any point between its fully opened or vertical position and its fully closed position, the amount of air discharged or circulated can be readily adjusted to the comfort of the operator. Also by positioning 30 the damper, as shown in Fig. 4, any back drafts occurring when the unit is not in use are prevented from entering the room.

Thus it is seen that I have provided a ventilating device with highly desirable features which is 40 compact, easily installed and highly efficient in its operation. It is conveniently disposed between studding in a wall. It can be used to quickly withdraw odors from a room or moisture laden air or it can circulate air as it is or warm it 45 as it passes through heating coils. It can, as shown and described, fit conveniently between the studding of the building. This device has particular usefulness in a bathroom or a kitchen.

It will of course be understood that various 50 changes may be made in the form, details, arrangement and proportions of the parts, without departing from the scope of applicant's invention, which generally stated, consists in a device 55 capable of carrying out the objects above set forth, in the parts and combinations of parts disclosed and defined in the appended claims.

What is claimed is:

1. A heating and ventilating device having in combination, a housing of general parallelopiped form and substantially rectangular in front elevation and disposable in a wall of a room and between a pair of vertically extending studding, said housing having lower and upper front openings disposed substantially in a common vertical plane, said upper opening providing an outlet into said room and said lower opening providing an intake for air from the said room, a fan in the lower part of said housing closely adjacent and having its inlet side facing said lower opening, a discharge duct secured to the top of said housing and extending upwardly between said studding and having a discharge end communicating with the atmosphere, a damper pivoted about a horizontal axis adjacent the top of said upper open-

ing and disposed in said housing at the rear of said upper opening and adapted to be swung to a front substantially vertical position for directing all of the air drawn through said lower opening up through said discharge duct or to be swung to a rearward position for directing all of said air through said upper opening into said room or to be positioned at some intermediate point to divide the passage of air by directing the same through both the exhaust duct and the outlet into the said room, means secured in upper opening extending across the same for warming air passing therethrough, and means for so positioning said damper whereby different amounts of the air in said room can be circulated through said housing and said air may be warmed if so desired.

2. A ventilating device adapted to be disposed between adjacent studding in a wall having in combination, a housing of general rectangular form in cross section and in front elevation and having an open front and an opening at its top, a member extending between said studding and supporting said housing, upper, lower and intermediate bars extending horizontally across said front forming upper and lower openings communicating with said room, a fan casing in the rear of said lower opening having an intake opening adjacent and aligned with said lower opening and having a discharge outlet at its top substantially horizontally aligned with said intermediate bar, a fan in said casing, a swinging damper hinged to said upper bar about a horizontal axis and adapted to extend vertically to said intermediate bar so as to close said upper opening and direct air from said discharge outlet upwardly through said top of said housing or to swing rearwardly with its bottom edge in the rear of said discharge outlet so as to direct air from said discharge outlet through said upper opening.

3. A ventilating device having in combination with adjacent studding in the wall of a room, a box-like housing disposed between said studding, said housing having an open front and an opening in its top, an outlet duct extending vertically from said latter opening upwardly between said studding to a point exteriorly of said room, said open front comprising upper and lower openings communicating with said room, a plate-like damper hinged at its upper edge about a horizontal axis adjacent the top of said upper opening and adapted to be disposed to close said upper opening, a fan in the rear of said lower opening, a bracket secured to said housing, a motor carried by said bracket having a driving shaft to which said fan is secured, said fan acting to draw air from said room through said lower opening and discharge the same upwardly through the top of said housing when said damper is in position closing said upper opening or through said upper opening when the lower end of said damper is swung rearwardly.

4. The structure set forth in claim 3, a plurality of spaced heating elements extending across said upper opening, and means for positioning said damper in an intermediate position so that part of the air drawn from said room is

discharged through the top of said housing and air is discharged through said upper opening and heated.

5. A heating and ventilating device having in combination, a housing of general parallelopiped form and substantially rectangular in front elevation and disposable in a wall of a room and between a pair of vertical studding, said housing having a partition dividing the same into upper and lower chambers, spaced bars extending transversely at the front of said housing between and at the remote upper and lower sides of said chambers respectively, a fan casing in said lower chamber, a fan in said lower chamber rotatable about a horizontal axis, said lower chamber having a front opening forming the inlet for said fan, a motor in the rear of said fan having a drive shaft secured to said fan, a bracket embracing said motor and having radially extending arms secured respectively to the lower pair of said bars, said fan casing having an outlet opening extending through said partition with an open end adjacent said partition, a conduit leading from the top of said upper chamber to the atmosphere, a damper pivoted to the upper of said bars about a horizontal axis, said upper chamber having an opening between the upper two of said bars, heating elements extending across said opening, a handle secured to said damper and extending to the front of said housing, said damper being movable to a substantially vertical position for closing the opening at the front of said upper chamber for directing air from said fan through said conduit and being movable to a rearward position for directing all the air from said fan into said room, past said heating elements and also being movable to intermediate positions for directing some of the air into said room and some of the air through said conduit.

6. The structure set forth in claim 5, and a grill secured to the front of said housing, said grill having an intermediate portion provided with an opening through which said handle extends, and provided with openings in front of said heating elements and also provided with vertical spaced openings in front of said lower chamber.
